UNITED STATES PATENT OFFICE

GRACE PENROSE, OF NEW PARIS, PENNSYLVANIA

HOLDER AND PROTECTOR FOR ARTIFICIAL FLOWERS

Application filed March 6, 1928, Serial No. 259,500. Renewed February 18, 1930.

The present invention consists of a holder and protector for artificial flowers and is especially adapted for use on graves.

An object of the invention is to provide a durable and substantial base which may be superimposed on the grave and is equipped with a transparent cover through which the flowers, carried by the base, are discernible.

A further object of the invention is to provide novel means for supporting the transparent cover on the base in a manner which prevents displacement of the cover without detracting from the appearance of the device.

15 A still further object of the invention is to provide an infrangible base which may be anchored in a grave and is used as a supporting medium for the flowers, the base being encompassed by a transparent cover through which the flowers are discernible.

The above and other objects of the invention will be apparent from the following description of the present preferred form of the invention, taken in connection with the 25 drawings, wherein

Figure 1 is a top plan view of a holder and protector constructed in accordance with the present invention, the cover thereof being shown in dotted lines;

30 Figure 2 is a bottom plan view of the base;

Figure 3 is a transverse sectional view taken on line 3—3 of Figure 1;

Figure 4 is a top plan view of a modified form of base;

35 Figure 5 is a transverse sectional view thereof, showing the cover in dotted lines;

Figure 6 is a bottom plan view of the form of base shown in Figures 4 and 5;

40 Figure 7 is a detail fragmentary side elevational view of another modified form of base and cover; and,

Figure 8 is a cross-sectional view taken on the line 8—8 of Figure 7, looking in the direction of the arrows.

45 The device of the present invention may consist of a base 9, as shown in Figures 1, 2 and 3 of the drawings, which is of oblong configuration and is made of metal or other suitable infrangible and preferably non-destructible material. Portions of the mar-

ginal edges at the sides and ends of the base are extended and depressed downwardly to provide supporting fingers 10, which preferably lie below the plane of the base for a purpose hereinafter set forth. The bottom 55 of the base is provided with a series of tubular legs 11 through the medium of which the base is anchored in the ground. By making the legs tubular, it is apparent that pressure on the base will urge the legs into 60 the ground and permit portions of the latter to enter the legs, so as to more firmly anchor the base.

The base is adapted to receive a transparent cover 12, as illustrated by the dotted lines 65 in Figures 1 and 3. The cover is preferably of circular configuration in cross-section and has the marginal edge thereof seated on the fingers 10. By counter-sinking the fingers 10, it is apparent that the cover 12 will completely encompass the base 9 to better retain 70 the cover and to produce a more artistic effect when the device is mounted on the grave.

The form of invention illustrated in Figures 4, 5 and 6, is similar to that illustrated 75 in Figures 1 to 3 inclusive, except that the base 9' thereof is of circular configuration and the supporting fingers 10' are located around the periphery of the base. The transparent cover 12' is circular to conform 80 to the shape of the base. This form of invention is used in the same manner as the form illustrated in Figures 1 to 3 inclusive.

The form of invention illustrated in Figures 7 and 8 of the drawings differs somewhat from that illustrated in the other figures of the drawings, in that a cylindrical supporting base 13 is provided, the lower end of which is adapted to be embedded in the top of the grave. Supporting fingers 85 10² are formed on the outer periphery of the base, approximately midway the ends of the latter. Between the fingers 10² and the top of the base I provide series of spaced lugs 14. The base is made of metal or other suitable 90 indestructible material and is adapted for the reception of a transparent cover 15. The cover in the present instance is of spherical configuration and is provided with a reduced base portion 16, which is adapted to be 95 100

sleeved over the upper end of the base 13 and is provided with an annular series of lugs 17 on its inner periphery which complement and are engageable between the series of lugs 14 formed on the base 13. The free end of the cover base 16 is mounted on the fingers 10². By interengaging the lugs 14 and 17 in the manner illustrated in Figure 7 of the drawings, independent movement of the cover on the base is prevented.

10 In use of the forms of invention illustrated in Figures 1 to 6 inclusive, the flowers are permitted to lie on the base in a horizontal position and are discernible through the transparent covers 12 and 12'. In the form of invention illustrated in Figures 7 and 8, the flowers are stood in an upright or vertical position, so that the upper ends thereof will project into the transparent spherical cover 15 while the stems rest on the top of the grave within the base 13. In all forms of the invention the base is made of indestructible material, so as to last for an indefinite period of time and when anchored in the grave after the teaching of the present invention, it will not be casually displaced. The transparent covers may be expeditiously removed when desired for the purpose of changing the flowers or cleaning the covers.

15 Although I have herein described the preferred forms of my invention, it is nevertheless to be understood that the device is susceptible of various changes in construction, proportion and arrangement of parts, within the scope of the claims hereto appended.

20 What is claimed is:

1. A holder and protector for artificial flowers including a base equipped with a series of supporting fingers below its upper margin, and a transparent cover engaged over said base in the depressions and with the fingers.

2. A holder and protector for artificial flowers, including an intransigible base anchored upon the ground and having portions thereof extended and depressed to provide relatively narrow supporting fingers beyond the margin of the base, and a transparent cover engaged over said base and with the fingers.

25 3. Means to hold and protect artificial flowers on a grave including a flower supporting base anchorable on the grave and equipped with integral fingers disposed below its upper marginal edge, and a transparent cover encompassing the top of the base and engaged in the depressions of said fingers.

4. Means to hold and protect artificial flowers on a grave including a hollow base anchorable on the grave and equipped with integral fingers countersunk beneath the top of the base, and a transparent cover engaged over said base and with said fingers.

30 5. Means to hold and display flowers on a grave, including a base for engagement with

the grave and equipped with depressed fingers formed at intervals around the base and integral therewith to be superimposed on the grave when the base is in position, and a transparent cover mounted on said base in engagement with the depressions of said fingers.
